UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF MICHIGAN.

IGNITION SYSTEM.

1,164,722.

Specification of Letters Patent. Patented Dec. 21, 1915.

Application filed August 5, 1910. Serial No. 575,853.

To all whom it may concern:

Be it known that I, RUSSELL HUFF, a citizen of the United States, and resident of Detroit, in the county of Wayne and State 5 of Michigan, have invented certain new and useful Improvements in Ignition Systems, of which the following is a specification.

This invention relates to ignition systems for motor vehicles, and its objects are to improve systems of the above type so that the parts thereof may be easily assembled, so that the conductors will be protected, and premature ignition of the charge in the engine cylinders prevented.

15 The invention will be described in connection with the accompanying drawings, in which,—

Figure 1 is an elevation of the exhaust side of a hydrocarbon engine, showing the 20 invention applied thereto; Fig. 2 is a plan view; Fig. 3 is a partial elevation from the inlet side of the hydrocarbon engine shown in Fig. 1; Fig. 4 is a detail of one of the switches; Fig. 5 is a detail perspective view 25 of one of the brackets.

Referring to the drawings, the engine is shown as of the multi-cylinder type, in which the cylinders 10 are cast in pairs and bolted to the crank case 11. An oil tank 12 30 is mounted between two of the cylinders and inside of the exhaust pipe 13, so that the oil in the tank will receive the heat from the exhaust pipe and the cylinder walls.

14 designates the intake manifold and 15 the water pipe which conducts the water away from the cylinder water jackets.

The oil tank is provided with breather or 20 vent tubes 16 which connect at their lower ends with the crank case and pass through the tank.

The magneto 17 driven from the motor is mounted on the crank case on the exhaust side of the engine and is provided with the usual high tension distributor 17^a and the 45 low tension circuit breaker 17^b. High and low tension conductors 17^c have connections with the distributor and circuit breaker respectively, and pass upwardly along side of the cylinders to the heads thereof. It will 50 be seen that these conductors pass between the exhaust pipe and the cylinders both of which are hot. In order to protect these conductors, a tube or casing 18 is provided which is of substantially L-shape and passes

upwardly along the cylinders and across the 55 tops thereof. This tube is secured to the tank 12 by means of a bracket 19 on the tube bolted or screwed to a bracket 20 secured to the tank 12 in any suitable manner. The cylinder heads have mounted therein spark 60 plugs 23 which are located above the inlet valves, and adjacent each spark plug is mounted a support or post 22 of insulating material, each of which has mounted thereon a switch member 24 which is arranged to co- 65 operate with a switch contact on the spark plug. A bracket 25 is mounted on top of each of the supports or posts and is provided with side flanges 26 which engage the sides of the posts and with ears 27 which are ar- 70 ranged to receive a pivotal member 28, which is pivotally connected to the switch member 24 so that the switch member will be supported on the bracket 25 for universal movement. The bracket 25 is secured to the 75 support or post 22 by means of a stud 29 which is threaded to receive a knurled nut 30, so as to form a binding post for one of the high tension conductors. The supports or posts 22 are provided with holes 32 for 80 receiving the conductors 17^c. Each spark plug is provided with a yoke 31 having a switch contact which is engaged by one of the switch members 24.

It is desirable to mount the magneto on 85 the exhaust side of the engine where it will not be near the carburetor so as to avoid danger of igniting the mixture in the carburetor or near the engine base at the intake side. This however necessitates that 90 the conductors from the magneto pass near the exhaust pipe where they will be exposed to heat and oil which may pass out of the breather tubes 16, causing deterioration of the insulation on the conductors. It is for 95 this purpose that the protective casing 19 is provided. It is objectionable however to place the wires so close together that they will be in inductive relation, in view of the fact that the inducting action of one circuit on another circuit may be great enough 100 to cause premature ignition of the charge in one of the cylinders. The protective casing therefore covers the conductors to no greater extent than is necessary to protect them 105 against the heated exhaust pipe and the exhaust side of the cylinders. After the wires have reached the tops of the cylinders they

are spread out and supported in spaced relation, one above the other, on the supports 22 and a central support 21. By thus spacing the wires not only will the inductive action be reduced to a minimum, but the insulation of the entire system is very much increased.

By separating the wires at a point midway between the cylinders, the conductors 10 can be connected to terminals on the tops of the posts 22 and these posts can be made of substantially the same height, which not only renders their manufacture cheap, but also renders the connection of the conductors to the terminals convenient, and, moreover, improves appearances.

By securing the tube 18 to the tank the manufacture and assembling is greatly cheapened and facilitated, since the tank 20 and tube may be made and assembled in the sheet metal shop. It will be understood that the tube 18 conducts four high tension wires leading to the spark plugs in case the motor is a four-cylinder motor, and a low and a high tension wire leading to the coil on the dash.

It is exceedingly difficult or practically impossible to machine and assemble the parts so that the switch member and the switch 30 contact on the spark plug will be in absolute alinement. By mounting the switch for universal movement on its supports it is not necessary then to locate the coöperating parts so accurately with respect to each 35 other. In addition, the switch can be swung

entirely out of the way when it is desired to remove a spark plug, which is quite an item in the cramped space which a motor in a motor vehicle occupies.

It is obvious that various changes may 40 be made in the details of construction without departing from this invention, and it is therefore to be understood that this invention is not to be limited to the specific construction shown and described. 45

Having thus described the invention, what is claimed is:

1. In apparatus of the class described, the combination of an engine cylinder, a bracket fixed to said cylinder, a spark plug 50 for said cylinder provided with a switch contact projecting therefrom, a switch comprising a pair of bars movable as a unit and adapted to simultaneously engage opposite sides of said contact, and a universal joint 55 connection between said switch and said bracket.

2. The combination with a hydrocarbon motor, and a spark plug therefor having a switch contact thereon, of a support adjacent said spark plug, a switch member adapted to coöperate with said switch contact, and a universal joint between said switch member and said support. 60

In testimony whereof I affix my signature 65 in presence of two witnesses.

RUSSELL HUFF.
